UNITED STATES PATENT OFFICE.

JAMES L. BUTLER, OF AKRON, OHIO, ASSIGNOR TO THE B. F. GOODRICH COMPANY, OF NEW YORK, N. Y., A CORPORATION OF NEW YORK.

TIRE-BUILDING MACHINE.

1,382,471.

Specification of Letters Patent. Patented June 21, 1921.

Application filed May 27, 1919. Serial No. 200,021.

To all whom it may concern:

Be it known that I, JAMES L. BUTLER, a citizen of the United States, residing at Akron, in the county of Summit and State 5 of Ohio, have invented a new and useful Tire-Building Machine, of which the following is a specification.

This invention relates to means for supporting and driving the ring core or mandrel of a machine for building pneumatic tires, and its object is to save time and labor in mounting and dismounting the core as compared with the usual plan of supporting the core on a chuck.

15 The invention relates more particularly to the supporting and driving of a tire-forming core in a vertical plane, and I have shown it applied to a machine having means for stretching a strip of rubberized fabric circumferentially over the core, to make an open-bellied casing. The machine illustrated is also provided with certain tools for smoothing the sides of the fabric, but it will be understood that the invention is 20 not wholly restricted to these features.

25 Of the accompanying drawings, Figure 1 is a front elevation of a tire-building machine embodying my invention. Fig. 2 is a vertical section on a larger scale, taken on the line 2—2 of Fig. 1, showing the core, together with its supporting and driving means.

The machine 10 is provided with a suitable 30 frame 11, and is adapted to receive a reel 12 of fabric and liner which is led around a geared stretcher drum 13, the liner being rolled up on a reel 14, and the fabric passing over a former 36 onto the annular tire-forming core 15, which is mounted to rotate in the same vertical plane with these 35 fabric feeding and stretching devices. The margins of the fabric are pressed into conformity with the contour of the core by means of suitable side tools 16, which may 40 be swung upwardly out of operative position in the usual manner. Other tools or appliances (not shown) may be employed for 45 rolling and trimming the fabric around the beads.

50 The core 15 is suspended on a shaft 20 mounted to turn in a suitable bearing 21 and driven by means of gears (not shown) by power delivered to the machine through a driving belt 22. The outer end of shaft 20 55 is of reduced diameter, forming a shoulder

23 against which a keyed driving-gear pinion 24, flanked by a pair of core-supporting roller flanges or disks 25, 25, is held by a nut 26.

The core 15 has secured to its inner periphery an internal driven gear 20 fastened in place by a plurality of pins 31. This ring is formed with teeth 32 adapted to mesh with those of the pinion 24 and is laterally extended on both sides of said teeth 65 to form two annular tracks 33, 33 which rest on the roller disks 25. This construction relieves the pinion teeth of the weight of the core and also maintains the desired axial position of the latter on the driving 70 shaft 20 by reason of the fact that the driven gear is straddled by the roller flanges 25.

35 is a flanged or circumferentially grooved guide roller mounted to turn loosely on a fixed frame stud 37 and straddling the 75 internal gear at a point located on the inner periphery of the core at an intermediate height, about 90 degrees from the shaft 20, on the side toward the stretcher drum 13. The flanges of this roller ride on the tracks 80 33, and said roller serves the double purpose of co-acting with the upper roller flanges 25 to maintain the core in its proper plane of rotation and of counteracting the 85 tendency toward a radial or pendulous thrust movement of the core in a right-hand direction as viewed in Fig. 1, due to the forward drive of the gear pinion and the backward resistance of the tensioned fabric.

In the operation of my improvement, the 90 core 15 is maintained in operative relation to its supporting and driving devices by gravity, and is or may be supported, driven and guided wholly from its inner periphery and at two circumferential points only of 95 said inner periphery. It may therefore be lifted out of the machine, or operatively located therein without moving any parts of supporting and driving mechanism, thus considerably reducing the amount of time 100 and labor heretofore devoted to these manipulations.

It will, of course, be understood that the particular form of embodiment of the invention may be considerably varied without 105 departing from its essential characteristics:

I claim:

1. In a machine for making pneumatic tires, the combination of an annular tire-forming core mounted to rotate in a verti- 110

cal plane and provided with gear-teeth on its inner periphery, roller means in an upper position engaging said inner periphery for rotatably supporting the core, and a driving-gear pinion engaging the gear-teeth on the core, said core being detachably maintained in operative relation to said roller means and driving gear by gravity.

2. In a machine for making open-bellied pneumatic tire casings, the combination of an annular tire-forming core mounted to rotate in a vertical plane, means for applying a strip of fabric longitudinally about the circumference of said core and stretching the middle of the fabric as it winds upon the core, an eccentrically-mounted driving shaft geared to the inner periphery of the core, and means acting against the core for opposing the thrust of the latter in its own plane due to the driving force and to the tension of the fabric.

3. In a machine for making open-bellied pneumatic tire casings, the combination of an annular tire-forming core mounted to rotate in a vertical plane, fabric supplying and stretching devices mounted in the same plane at one side of the core, a thrust-resisting roller engaging the inner periphery of the core on the side toward said fabric-supplying and stretching devices, roller means in an upper position for supporting said core from its inner periphery, and a driving shaft geared to the inner periphery of said core for rotating the latter.

4. In a machine for making open-bellied pneumatic tire casings, the combination of an annular tire-forming core mounted to rotate in a vertical plane, and devices eccentric to the axis of said core for guiding and driving the core from its inner periphery, said devices being detachably maintained in operative relation to the core by the weight of the core and including means for resisting both axial and radial thrusts.

5. In a machine for making open-bellied pneumatic tire casings, the combination of a tire-forming core provided on its inner pe-

riphery with an annular row of gear teeth located between a part of annular tracks, and an eccentrically-mounted shaft having a driving-gear pinion engaging said gear teeth and also having a pair of roller members engaging said tracks.

6. In a machine for making open-bellied pneumatic tire casings, the combination of a tire-forming core mounted to rotate in a vertical plane and formed on its inner periphery with an internal gear flanked by a pair of annular tracks, and a shaft mounted in an upper position eccentrically of said core, said shaft having a driving-gear pinion engaging said internal gear and a pair of roller flanges straddling the gear and engaging said tracks for supporting the weight of the core and opposing axial displacement thereof in both directions.

7. In a machine for making open-bellied pneumatic tire casings, the combination of a tire-forming core mounted to rotate in a vertical plane, means located in an upper position eccentric to the axis of the core for supporting and driving the core from its inner periphery, and eccentrically-mounted roller means located at an intermediate height and engaging the inner periphery of the core for resisting radial and axial thrusts thereof.

8. In a machine for making open-bellied pneumatic tire casings, the combination of a tire-forming core mounted to rotate in a vertical plane and provided on its inner periphery with an internal gear flanked by a pair of annular tracks, a shaft mounted eccentrically in an upper position and having a driving-gear pinion engaging said internal gear and a pair of roller flanges straddling said gear and engaging the tracks, and a guiding device mounted eccentrically at an intermediate height and having roller flanges straddling said internal gear and engaging said tracks for resisting radial and axial thrusts of the core.

In testimony whereof I have hereunto set my hand this 23 day of May, 1919.

JAMES L. BUTLER.
